US00D983407S

(12) **United States Design Patent** (10) **Patent No.:** **US D983,407 S**
(45) **Date of Patent:** **** Apr. 11, 2023**

(54) **AMPULE CRUSH TOOL**

(71) Applicant: **Verrica Pharmaceuticals Inc.**, West Chester, PA (US)

(72) Inventors: **Eugene R. Scavola**, Charlottesville, VA (US); **Paul Daly**, Plymouth, NH (US); **Gregory Alcorn**, Valley Forge, PA (US); **Vicki Fluck**, Quakertown, PA (US)

(73) Assignee: **Verrica Pharmaceuticals Inc.**, West Chester, PA (US)

(**) Term: **15 Years**

(21) Appl. No.: **29/755,448**

(22) Filed: **Oct. 20, 2020**

(51) **LOC (14) Cl.** **24-99**

(52) **U.S. Cl.**

USPC **D24/231**

(58) **Field of Classification Search**

USPC D24/108, 220, 224, 114, 130, 231, 230, D24/164, 222

(57) **CLAIM**

The ornamental design for an ampule crush tool, as shown and described.

DESCRIPTION

FIG. 1 is a top, front, and right side perspective view of an ampule crush tool according to our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The dot-dash broken lines represent boundaries of the claimed design and form no part of the claimed design. The dash-dot broken lines depict portions of the ampule crush tool that form no part of the claimed design.

1 Claim, 6 Drawing Sheets
